INFLATABLE PREFABRICATED STRUCTURE
William H. Fischer, Redding, Conn., assignor to Air Inflatable Products Corporation, a corporation of Delaware

Original application Feb. 8, 1963, Ser. No. 257,314.
Divided and this application Oct. 12, 1964, Ser. No. 403,297

9 Claims. (Cl. 135—1)

This invention relates to inflatable transportable structures, and more particularly to prefabricated enclosures which may be quickly erected by inflation at the site. This application is a division of my copending application S.N. 257,314 filed February 8, 1963.

Temporary prefabricated structures such as inflatable "radome" enclosures for radar or communication antennas present serious problems of weakness under wind loading, erection difficulties, and the need for constant pressurizing of the entire interior of the structure, requiring double-door air-locks or the like to maintain internal pressure. Inflatable single-skin balloon-like "radomes" possess the structural strength to support their own weight when inflated, but extreme loading conditions presented by high wind loads often cause the failure of such structures, since they possess very little structural stiffness and rigidity.

Prior art inflated radomes require considerable sealing and caulking around the juncture of the tower and radome base and around the air-lock and air-lock doors, in order to maintain their inflated shape.

Single-skin prior art radomes are also subject to tearing or ripping on the radar or communications' antennas during high winds. This is a particularly serious problem if there is "dimpling" of the radome skin so that it catches on a rotating radar reflector, for example. When such a tear occurs, the radome skin generally splits from top to bottom as air pressure rushes through the break. The ripped radome skin then clings to the radar reflector and acts as a large sail. In high winds the radar may be swept from the radar tower and destroyed.

The prefabricated structures of the present invention provide unusually high strength coupled with unexpected convenience during handling and erection of the structures. They incorporate a unique construction taking advantage of a double walled inflatable cellular panel arrangement. The panels may be conveniently fabricated and transported to the erection site, where their handling and inflation is greatly simplified by their unusual construction. In the event of a tear in a cellular panel, there is no great rush of air through the break. This is due to the baffling structure between each cellular chamber in the panels. The break can be easily patched over the low velocity air issuing from the disrupted cellular chamber. Thus a break in a panel wall does not endanger the whole structure and the equipment it houses, since there is ample time to patch the break.

Accordingly it is a principal object of this invention to provide lightweight structures which may be fabricated, transported and erected with maximum convenience.

Another object of the invention is to provide prefabricated enclosures of the above character affording high strength and stiff rigidity in the completed structure.

A further object of the invention is to provide inflatable structures of the above character which present minimum risk of fast deflation upon being punctured or torn.

Other objects of the invention will in part be obvious and will in part appear hereinafter.

The invention accordingly comprises the features of construction, combinations of elements, and arrangement of parts which will be exemplified in the constructions hereinafter set forth, and the scope of the invention will be indicated in the claims.

2

For a fuller understanding of the nature and objects of the invention, reference should be had to the following detailed description taken in connection with the accompanying drawings in which:

5 FIGURE 1 is a perspective elevation view of a prefabricated enclosure incorporating the present invention.

FIGURE 2 is an enlarged fragmentary view of the interpanel locked seam construction of the enclosure illustrated in FIGURE 1.

10 FIGURE 3 is a further enlarged fragmentary elevation view of the sector panel locking elements shown in FIGURE 2.

FIGURES 4 and 5 are top and plan views respectively showing the elements of FIGURE 3 in their unlocked and locked juxtapositions.

15 FIGURES 6 and 7 are enlarged sectional end elevation views showing the woven fabric forming the internal and external skins of the structures of the invention in successive stages of their fabrication.

20 FIGURE 8 is an enlarged fragmentary perspective view showing a cross-section of the wall of the enclosure illustrated in FIGURE 1.

FIGURE 9 is a perspective view showing one compound curved panel forming a portion of the enclosure illustrated in FIGURE 1.

25 FIGURE 10 is a plan view of two web elements shown in FIGURE 8, and

FIGURE 11 is a greatly enlarged fragmentary cross-sectional perspective view of the structure shown in FIGURE 8 broken away to show the construction details more clearly.

Similar reference characters refer to similar parts throughout the several views of the drawings.

FIGURE 1 shows a prefabricated structure incorporating the present invention, in the form of a cylindrical, round-topped, beehive-shaped enclosure generally indicated at 20. This structure is formed of six compound-curved inflatable panels 28 or 30 having the general appearance of the panel 28 shown in FIGURE 9. All of

35 40 these doubly-curved panels are formed of two generally parallel walls or "skins" of substantially air-impermeable material, spaced apart as shown in FIGURES 8 and 11 by a number of web elements bridging the intervening space and contributing form and shape to the resulting structure upon inflation. Compressed air under low pressure is introduced into the spaces between the two outer skins, producing inflation of the panels illustrated in FIGURE 9, and these panels are firmly locked together along their juxtaposed edges by the locking elements illustrated in FIGURES 2-5.

45 50 As indicated in FIGURE 1, the structure 20 is anchored in position at its site by a large plurality of guys 22 securing its lower periphery to embedded stakes 24. The guys 22 are joined to the inflatable enclosure 20 by attachment to the successive peaks of the scalloped guy flaps 26, integrally joined to the lower periphery of each of the panels 28 and 30 which fit together to form the complete structure 20.

The inflatable sector panel 30 differs from the panel 28 only in the presence of an entrance portal 32 incorporating closable mating flaps 34 spanning the portal 32. Otherwise the entrance panel 30 closely resembles the unapertured panels 28 comprising the remainder of the structure 20.

55 60 65 The separate gore-like panels 28 and 30 are firmly locked together along their juxtaposed curved edges 36 by lock flaps or bands 38 having one edge shaped in a scalloped configuration presenting outwardly projecting peaks 40, shown in FIGURE 2, each having a helical lock 42 protruding therefrom and which may be matingly interleaved with a corresponding helical lock 44 of opposite pitch as indicated in FIGURE 3. The helical wire-shaped

lock members are firmly anchored to the peaks 40 by clamps 46 riveted in position flanking a nylon bearing block 48, and a "bolt rope" 49 integrally joined along the curved or scalloped edge of the flap 38 may pass between the clamp 46 and the bearing block 48 to transmit its tension directly to the helical lock members 42 and 44.

As shown in FIGURES 4 and 5, the lock members 42 and 44 are easily interfitted over a portion of their curved peripheries by interleaving the turns of the facing oppositely pitched helical lock members, and a lock wire 50 is then inserted to retain the interleaved helices in their locked engagement. The lock members 42 and 44 and the riveted clamps 46 are preferably formed of weather-proof stainless steel, extending the useful life of the structure 20.

The successive steps in the fabrication of the panels 28 and 30 are shown in FIGURES 6, 7 and 11. The first step in the fabrication of the sector panels 28 is the weaving of a double layer sheet of fabric 52 having an upper layer 54 and a lower layer 56, these layers being integrally interwoven at a series of predetermined spaced junction lines extending across the entire loomed width of the double layer fabric, which may extend to 54 inches or more. The length of the interwoven junction lines 58 over which the separate panels 54 and 56 are integrally interwoven may be any desired number of fiber diameters, with preferably 10 or 12 or even more fiber diameters being incorporated in each interwoven junction 58. The space between each of the adjacent interwoven junctions 58 is predetermined, to provide the desired curvature in the panel ultimately fabricated therefrom, as will be more fully explained below.

The next successive steps in the fabrication of the panel 28 are illustrated in FIGURE 7, where each span of the lower layer 56 is shown cut away with the central strip 60 being removed to leave integral tabs 62 protruding from the junctions 58 along one side of the woven sheet material 52. A layer of impregnated air-impervious sheet material 65, which may be neoprene-impregnated Dacron fabric, for example, is cemented to the entire surface of the sheet 52 on the opposite side from the protruding tabs 62. The formation of the double-skinned inflatable panel 28 is illustrated in FIGURES 8 and 11, where the outer wall layer 52 is positioned with its protruding tab 62 facing a similar inner sheet 52a having similar tabs likewise facing the tabs on the opposed sheet 52.

A series of web panels 64 have their elongated opposite edges sandwiched between and firmly cemented to the tabs 62 protruding from each junction 58 on each of the facing wall sheets 52 and 52a as shown in FIGURE 8. The enlarged fragmentary view of FIGURE 11 shows the successive steps in the construction of the cellular inflatable panel 28, beginning at the upper portion of this figure, where the protruding tabs 62 are shown fanned apart and ready to receive a web panel 64. In the center of FIGURE 11 the web 64 is shown in position, with its elongated edge 66 projecting between the fanned apart protruding tabs 62. The near edge 68 of the web panel 64 has the corresponding tabs 62 of the fabric sheet 52a firmly cemented down on its opposite sides to sandwich and bond the web 64 firmly to the fabric sheet 52a along the junction 58.

A completed sandwiched web construction is illustrated toward the bottom of FIGURE 11 where both elongated edges of another web 64 are shown sandwich-bonded between the respective tabs 62 protruding inwardly from the facing junctions 58 of the respective panels 52 and 52a. The resulting bonded webs 64 define with the facing fabric panels 52 and 52a a series of successive longitudinally elongated air chambers 70. The web 64 may be porous and permeable to air passing between adjacent chambers 70, and these chambers may also be connected by end passages not shown on the drawings for convenient inflation of the completed panel member 28.

The compound curvature of the final fabricated panel

28, best shown in FIGURE 9, is produced by the dimensioning of the respective components of the structure. As indicated in FIGURE 8, the generally vertical or right circular cylindrical lower portion of the panel 28 is produced by spacing the parallel junction lines 58 of the inner fabric panel 52a successive equal distances apart, these distances being the same as the distances between the corresponding junction lines 58 on the facing outer panels 52. Thus both inner and outer walls of the lower chambers 70a are of equal height, and the lower or right circular cylindrical portion 72 of the panel 28 is curved only in a single direction, about a vertical axis. This curvature is determined by the radius of curvature of the curved elongated edges of the webs 64a, shown in top plan view in FIGURE 10.

By contrast the compound curvature of the upper, arched section 74 of the panel 28 is produced by moving the junction lines 58 on the inner panel 52a successively closer together over this upper portion of the panel. By this means the upper chambers 70b have their outer walls slightly taller than their inner walls, providing successive angular displacement of the successive webs 64b over the upper portion of the panel 28, producing the inward leaning configuration of the completed panel. This curvature about a generally horizontal axis is combined with sharper curvature at a diminishing radius about a vertical axis with successive and more sharply curved web 64b, as shown in FIGURE 10, where the curvature and radius of curvature of an upper web 64b may be compared with those of a lower web 64a.

The successive and more sharply curved webs combined with the diminished relative height of the inner walls of the chambers 70b produces the arched compound curvature illustrated in FIGURE 9, permitting the successive panels 28 and 30 to be joined along the abutting edges 36 to form the completed structure of FIGURE 1.

If the progressive variations in the curvature of the web 64 and the respective heights of the inner and outer walls of the chambers 70b are generally uniform, the smooth curvature illustrated in FIGURES 1 and 9 will result. Non-uniform rates of variation of these variables will produce non-uniform curved surfaces which may if desired produce a "sharp" edged contour comparable to the "hard chine" of flat-bottomed and V-bottomed boats, as contrasted with the smoothly curving hull surfaces and profiles of an "hour-glass" shaped, deep-keel sailboat hull.

The panels 28 are preferably made of weather resistant impregnated Dacron fabrics, woven in the double layers shown in FIGURE 6 and subjected to a heat setting treatment for cleaning and preshrinking the fabric prior to the fabrication steps described above. The layer 65 may be formed of closely woven nylon or Dacron fabric, preferably coated on both sides with one or more thinly doctorated layers of neoprene or vinyl material, thus impregnating this outer layer 65 to enhance air retention, strength and abrasion resistance of the resulting structure. These impregnating materials are generally applied in solvent solutions from which the solvent is evaporated by heat during the coating process to leave the dry impregnated fabric ready for the fabrication of the panels 28.

After the removal of the central strip 60 to leave the protruding tabs 62, these tabs 62 and if desired the adjacent surface of the fabric sheet 52 is covered with a thin coating of neoprene-solvent solution to fill the interstices of the tabs 62, stiffening or "sizing" these tabs for subsequent use and priming the tabs to produce a firmer bond sandwiching the panel 64 between the mating tabs 62.

Automatic processing equipment is easily adapted to produce the desired radius of curvature for each of the web panels 64 and the loom on which the double layer fabric panels 52 are woven can be adjusted to space the junctions 58 successively closer together at the precise predetermined distances required to produce the desired curvature of the resulting panels 28.

To maintain the position orientation of the components, a "match mark" system of successive marks spaced at small intervals, such as 3 inches or 6 inches, along the mating edges of the fabric will facilitate the desired registration of the component elements.

The "successively piled," horizontal orientation of the chambers 70, producing the beehive appearance shown in FIGURE 1, provides a unique construction advantage during the erection operation. The panels 28 may be laid out in a generally radial direction from the center of the area which the structure 20 is to occupy, and as inflation proceeds the chamber 70 will inflate and elongate to provide lightweight tubular cell structures which will roll and move freely about their elongated axes to facilitate the successive inflation orientations of the panel 28, while resisting endwise distortion which might throw the inflating panel out of alignment and cause twisting or knotting of the panel as it inflates to its erect position.

The inflatable enclosures of the present invention are well adapted for convenient erection in as short a period as three hours by a practiced team of erectors, and they may be dismantled with equal ease. These structures require low pressures of less than one pound per square inch to raise them to their erect position, and an internal inflation pressure less than 2 p.s.i. will stiffen the resulting structure to withstand wind loadings produced by hurricane force winds of 100 miles per hour.

The extremely lightweight structure illustrated in FIGURE 1, 43 feet high and 43 feet in diameter, is formed of 6 panels each weighing less than 300 pounds and producing a total structure weight of only 1,700 pounds. This flexible enclosure, with its panels inflated and locked together in the manner shown in FIGURES 1 and 2, is capable of supporting a 2,000 pound weight suspended inside the center of its dome.

While a more airtight wall can be made by adding additional layers 65 to one or both walls of the panels 28, the addition of this extra weight is preferably eliminated by providing an air compressor 76 connected to supply additional compressed air to the panels whenever required, at the command of pressure sensitive limit switches 78, as shown in FIGURE 9.

The desired objectives of convenience in fabrication, transportation and erection are thus combined with extremely lightweight, structural rigidity and stiffness to provide temporary or semi-permanent prefabricated structures and enclosures which are well adapted to provide shelter for men and equipment under severe adverse conditions of wind and weather. The absorption or reflection of external radiation may be controlled by the incorporation of metallized or vapor-deposited layers of aluminum in one or both of the surface walls of the panels 28 to produce "Thermos" bottle or "greenhouse" effects as desired. While the interior of the resulting structures need not be pressurized to provide structural rigidity, breathable atmospheres may be maintained at the desired pressures, higher than any rarified atmospheres outside the structure if desired.

It will thus be seen that the objects set forth above, among those made apparent from the preceding description, are efficiently attained and, since certain changes may be made in the above constructions without departing from the scope of the invention, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention, which, as a matter of language, might be said to fall therebetween.

I claim:

1. A self-supporting prefabricated double walled inflatable structure comprising in combination

- (A) a plurality of curved sector panels each having an inner wall and an outer wall;
- (B) a plurality of junction lines extending transversely across each said wall, with the width of said outer wall being greater than the corresponding width of said inner wall along each junction line,
- (C) both said walls having juxtaposed tabs secured along said junction lines, each of said juxtaposed tabs being joined together to join said walls in spaced relationship along said junction lines,
- (D) end closure means joining the peripheries of said inner wall and said outer wall and forming with the facing surfaces of said inner wall and said outer wall a successively arrayed plurality of adjoining longitudinally-curved inflatable cell chambers joined to form a cellular double-walled inflatable sector panel having an arcuately curved shape upon inflation,
- (E) and edge attachment means for locking the abutting edges of said sector panels together to form an enclosure.

2. The inflatable structure defined in claim 1 in which the junction lines on said inner wall are spaced closer together over at least a portion of the area of said inner wall than are the junction lines of said outer wall, whereby each sector panel upon inflation assumes a shape having compound curvature.

3. The structure defined in claim 1 in which said edge attachment means include

- (A) pairs of interleaved interlocking helical coil springs having opposite pitch directions,
  - (B) and a locking band
    - (1) having a scalloped edge presenting edge-wise protruding points
    - (2) and an opposite edge integrally joined to the outer face of each said sector panel adjacent the abutting edge thereof,
  - (C) one spring of each said pair being firmly secured to a protruding point of one said locking band and the other spring of said pair being firmly joined to an opposed point on a similar locking band secured to the abutting edge of the adjoining sector panel and aligned for interleaved engagement with its companion spring, and
  - (D) a flexible rod member positioned between the interleaved coils of said springs after engagement to secure them against disengagement,
- whereby said double walled inflatable structure is firmly secured in its erected condition.

4. A self-supporting prefabricated double walled inflatable structure comprising in combination

- (A) a plurality of curved sector panels each having an inner wall and an outer wall;
- (B) a plurality of substantially flat webs having elongated concentrically curved edges respectively joined to tabs extending along junction lines of the facing surfaces of said inner wall and said outer wall to form a successively arrayed plurality of adjoining longitudinally-curved inflatable cell chambers,
- (C) with the width of said inner wall corresponding to the length of its mating curved longitudinal edge of said web and the width of said outer wall corresponding to the length of its mating curved longitudinal edge of said web;
- (D) end closure means joining the peripheries of said inner wall and said outer wall to form a cellular double-walled inflatable sector panel having an arcuately curved shape upon inflation corresponding to the shape of said webs
- (E) and edge attachment means for locking the abutting edges of said sector panels together to form an enclosure.

5. The self-supporting prefabricated double walled inflatable structure defined in claim 4 wherein said webs are porous whereby air may pass slowly through said webs to adjoining cell chambers.

6. A self-supporting prefabricated double walled inflatable structure comprising in combination
- (A) a plurality of curved sector panels each having an inner wall and an outer wall of woven material;
  - (B) a plurality of substantially flat webs having elongated concentrically curved edges respectively joined to tabs interwoven with the walls along junction lines of the facing surfaces of said inner wall and said outer wall to form a successively arrayed plurality of adjoining longitudinally-curved inflatable cell chambers,
  - (C) with the width of said inner wall corresponding to the length of its mating curved longitudinal edge of said web and the width of said outer wall corresponding to the length of its mating curved longitudinal edge of said web;
  - (D) end closure means joining the peripheries of said inner wall, said outer wall and said webs to form a cellular double-walled inflatable sector panel having an arcuately curved shape upon inflation corresponding to the shape of said webs;
  - (E) and edge attachment means for locking the abutting edges of said sector panels together to form an enclosure.
7. A self-supporting prefabricated double-walled, inflatable structure comprising, in combination,
- (A) a plurality of inflatable sector panels
  - (1) each having inner and outer walls of flexible material,
  - (a) said walls being spaced when inflated,
  - (B) said panel walls being spaced by a plurality of webs attached along the web edges at wall junction lines to form a plurality of inflatable cellular chambers,
  - (1) said webs being curved along their attached edges,
  - (2) said webs being progressively shorter at the

5
1015
20

25

30

upper portion of each of said panels to provide a peaked upper portion on each panel, (3) said junction lines being spaced closer together along the upper portion of said inner wall than for corresponding junction lines on said outer wall to provide a compound curvature at the upper portion in the shape of a portion of a dome,

(C) and edge attachment means for securing the abutting of edges of said sector panels together to form an inflatable, double-walled enclosure approximately circular in axial cross-section and having a domed top.

8. The inflatable structure defined in claim 7 wherein said junction lines have protruding tabs secured thereto, along, the corresponding tabs for the inner and outer wall junction lines being secured to said webs.

9. The inflatable structure defined in claim 8 wherein said tabs are interwoven with the flexible material of said walls along said junction lines.
